UNITED STATES PATENT OFFICE.

JOHN H. BURR AND FRANK G. BURR, OF WHITMAN, NEBRASKA.

HOISTING AND TILTING DEVICE.

1,280,155.

Specification of Letters Patent.

Patented Oct. 1, 1918.

Application filed November 23, 1917. Serial No. 203,512.

To all whom it may concern:

Be it known that we, JOHN H. BURR and FRANK G. BURR, citizens of the United States, residing at Whitman, in the county 5 of Cherry and State of Nebraska, have invented a new and useful Hoisting and Tilting Device, of which the following is a specification.

This invention has reference to a hoisting 10 and tilting device, adapted particularly for use in elevating and tilting over motor vehicles for facilitating access to the bottom thereof to make repairs and adjustments.

The object is to provide a portable, simply 15 constructed device which is light in weight, which may be manufactured and produced upon the market at relatively small cost, and a device which is compact and may be easily handled in relatively small space.

Another object of this invention is to provide a frame upon which the motor vehicle 20 may be driven, a hand operated means for lifting up one side of the frame and tilting the vehicle over toward one side, the hand 25 operated means embodying certain constructions which hold the frame for limited movement to prevent overturning and damage to the vehicle and to insure the positive return of the vehicle carrying frame even though 30 should the same be disposed with its lower edge within the vertical plane of its upper edge.

The invention also embraces certain other 35 objects and advantages which will herein- after be pointed out and understood from the following detailed description of the present preferred embodiment of this invention, the same being illustrated in the accompanying drawings wherein—

Figure 1 is a top plan view of a vehicle 40 elevating and tilting device constructed according to the present invention.

Fig. 2 is an end elevation of the same, the 45 dotted lines showing a motor vehicle in position on the device and being tilted at substantially forty-five degrees.

Fig. 3 is a fragmentary enlarged horizontal 50 section through one of the standards and the parts adjacent thereto.

Fig. 4 is a fragmentary vertical section 55 taken through the device at one side of one of the posts, showing the adjacent part of

the vehicle receiving frame in partly tilted position.

Fig. 5 is an end view of the device, showing a slight modification in the raising and 55 lowering means.

Referring to these drawings, the device comprises a frame portion or body part made up of a pair of spaced apart rails 10 of 60 channel iron construction and with preferably the flanges upturned to form a guideway within each rail 10. The rails 10 are transversely disposed with respect to the longitudinal axis of the device and are suitably held in spaced apart relation such as by means of a pair of crossed tie rods 11. The tie rods 11 are secured at opposite ends by bolts 12 to the rails 10 at one side of the 65 machine.

The rails 10 are each provided with a standard or post 13 which is seated in a socket 14 at its lower end and clamped to the rail 10 by bolts or the like. The standards are arranged near the ends of the rails 75 10 and at one side of the device. Braces 15 are secured at their lower ends to the rails 10 by preferably the outer bolts 12 which are also employed for holding the tie rods 11 in place. The upper ends of the braces 15 80 are secured to the standards 13 near the upper ends of the latter by bolts 16.

Normally resting across the rails 10 is a vehicle receiving frame formed of a pair of side bars 17 of angle iron construction and 85 provided with relatively deep base flanges upon which the wheels of the vehicle are adapted to roll. The bars 17 are held apart by pairs of crossed brace rods 18 secured by rivets 19 or the like to the bars 17 near the 90 ends of the latter. The bars 17 are further reinforced by straps 20 which are secured at opposite ends to the undersides of the base flanges of the bars by the said rivets or bolts 19. The inner ends of the straps, or 95 the ends adjacent the standards 13, are longitudinally slit to form a pair of tongues on each strap 20 which are twisted into a plane at right angles to that of the strap 20. These tongues or ears 21 have pivoted between them the lower end of a flat link 24 100 which passes up through a tongue 22 projecting from a yoke 23 which embraces the standard 13. The yoke 23 is preferably

formed from a length of strap metal which is overturned and rounded near its free ends to slidably engage the standard, and the tongue 22 is formed by the overturned intermediate portion of the yoke which projects outwardly from the standard.

Preferably, the flat link 24 is secured in the tongue 22 by a pin and projects down from the tongue and is pivoted to the ears 21 by a pin 25. The rear ends of the yokes 23 are closed by transverse rollers 27 having grooved peripheries conforming in contour to the cylindrical exterior surfaces of the standards, the rollers 27 being supported upon transverse pins or the like in the free ends of the yokes. An elevating cable 28 is attached at one end to the upper end of each bar 24 and passes over a pulley 29 seated in the upper end of each standard 13, the cables 28 passing down at the inner sides of the standards 13 and being secured to a longitudinal shaft 30 which is journaled near its opposite ends in the braces 15 and at a suitable height.

25 The shaft 30 has a crank arm 31 on its end adapted to be turned by hand for rotating the shaft 30 and winding the cable 28 thereon. The cable 28 is wound upon the shaft 30 preferably between the posts 13, and a second cable 32 is wound upon each end of the shaft 30 beyond the posts 13. The cables 32 are connected at their free ends to steady arms 33 which are pivotally mounted upon the inner side of the vehicle receiving frame. The ends of the arms adjacent the frame are pivoted on pins 34 which pass through the lower ends of brackets 35 secured vertically upon the inner side of said frame, the brackets 35 rising above the vehicle supporting frame and having secured thereto tension springs 36 which are fastened at their other ends to the rear extremities of the arms 33. The springs 36 normally urge the arms 33 upward and thus maintain the cables 32 taut at all times. The inner ends of the arms 33 project beyond the brackets 35 and form shoulders or supports 37 adapted to bear against the underside of the vehicle receiving frame to limit the downward swinging of the arms 33. The bars 17 are bent down at opposite ends to form inclined ways adapted to elevate the wheels of the vehicle and to admit the gradual depositing of the vehicle from and upon the ground with reference to the vehicle receiving frame.

60 The outer side of the vehicle receiving frame is provided with a pair of rollers 38 mounted in brackets 39 which are riveted or otherwise secured to the outer bar 17, the wheels 38 being arranged to travel in the rails 10 and to support the frame and the vehicle thereon when the inner side of the frame is elevated. The brackets 39 are tilted 65 downward at a slight angle to position the

rollers 38 in contact with the rails 10 at practically all times.

In Fig. 5 the modification embraces a cable 40 which is trained over the pulley 29 and which extends downwardly and outwardly over the vehicle receiving frame and is attached to the outer bar 17 thereof at 41. The tension cable 42 is connected to the outer bar 17, passes through a pulley block 43 mounted on the outer end of the adjacent rail 10, and extends inwardly along the rail to a pulley 44 mounted on the inner end of the rail 10, and from the latter pulley to the shaft 30 beyond the post 13. This construction prevails at each end of the device, and in this instance the posts 13 must be spaced apart a distance greater than the length of the vehicle placed upon the elevating frame so that the cables 40 will clear the ends of the vehicle.

85 The inner side of the vehicle supporting frame has an ear 45 opposite each post 13 and which is pivoted by a pin 46 to a collar 47 which surrounds the lower end of each post 13 and serves as an anchor for the inner 90 side of the frame. When this modified form is used the rails 10 must extend rearwardly of the posts 13 a distance beyond the center of gravity of the vehicle mounted on the tilting frame.

95 When the modified structure is used, a vehicle is run up upon the tilting frame with the wheels supported on the bars or rails 17. The vehicle has its wheels fastened to the bar 17 by a strap 48 or the like, such 100 as shown in Fig. 2. The operator now turns the crank handle 31 and rotates the shaft 30 in a direction to wind the cable 40 thereon and release the cables 42 therefrom. The outer side of the tilting frame may thus be 105 raised to tilt the vehicle over to one side so that easy access may be had to the parts located upon and adjacent the running gear. Any suitable means may be provided for holding the shaft 30 from turning to hold 110 the vehicle in tilted position. When it is desired to lower the vehicle the shaft 30 is turned in an opposite direction to wind the cable 42 thereon and to unwind the cable 40 and thus draw the tilting frame down into 115 position upon the tracks 10.

120 In the preferred form when the shaft 30 is turned in one direction the cable 28 lifts the yoke 23 upon the standard 13 and thus draws the inner end of the tilting frame up and holds said end of the tilting frame practically in the same vertical plane throughout its movement. The outer end of the tilting frame is thus drawn inwardly toward the post 13 and the roller 38 reduces frictional 125 contact between the frame and the track 10, and takes up the major portion of the weight of the vehicle. In this instance the strap 48 is secured about the inner bar 17 and the adjacent wheels of the vehicle. Of course this 130

operation takes place simultaneously at the opposite ends of the device, and the posts 13 may be spaced apart any suitable distance to provide a strong and stable device.

- 5 As the tilting frame is raised, the tension cable 32 is unwound from the shaft and the inequalities in the relative movements of the cables 32 and the tilting frame are taken up by the tension springs 36 which admit the 10 swinging of the arms 33 downward as the frame is raised.

When it is desired to lower the vehicle, it is only necessary to turn the shaft 30 in an opposite direction to wind the cable 32 thereon and draw the cable and the arm down until the shoulder 37 of the adjacent arm engages the underside of the tilting frame. The arms 33 are utilized chiefly in preventing the vehicle from turning suddenly over on its side, and for throwing out the free end of the tilting frame from the posts should the tilting frame be raised sufficiently to lie in a vertical plane. The return of the tilting frame to normal position 25 is thus positively assured as the cable 32 draws the frame back to lowered position and the cable 28 gradually takes up the weight of the vehicle.

It is of course understood that various 30 changes and modifications may be made in the details of construction and design of the above specifically described embodiment of this invention without departing from the spirit thereof, such changes and modifications 35 being restricted only by the scope of the following claims.

What is claimed is:

1. In a vehicle hoisting and tilting device, the combination of a body frame including 40 an upright at one side, a vehicle receiving frame supported on the body frame, and a hoisting means associated with said upright and connected to the adjacent side of said vehicle receiving frame for lifting said side 45 of the frame to tilt the same, and lowering means connected to the hoisting means and to said vehicle receiving frame for drawing the latter down into normal position upon the release of the hoisting means, said lowering means including a member for moving the other side of said frame away from the upright during the lowering of said adjacent side of the frame.

2. In a vehicle hoisting and tilting device, 55 the combination of a body structure equipped with a post at one side, a laterally movable vehicle receiving frame resting on the structure, a shaft supported by the structure near the base of the post, a hoisting cable carried by the post and connected at one end to the adjacent side of the frame and at its other end to the shaft for raising said side of the frame when the shaft is turned in one direction, and a second cable connected to said 60 shaft and wound thereon in a direction op-

posite to that in which the first cable is wound, said second cable having connection with said side of the frame to draw the same down as the first cable is unwound, the other side of the frame being adapted to slide over 70 the structure toward and from the post to admit tilting of the frame.

3. In a vehicle hoisting and tilting device, the combination of a body structure equipped with a post, a tilting frame resting on the 75 body structure and adapted to receive a vehicle thereon, a hoisting cable trained over the top of the post and having connection with the adjacent side of the tilting frame, a second cable connected to said side of the 80 frame, a single winding element connected to both of said cables for alternately winding and unwinding the same to raise and lower said side of the frame, and transverse bearing members extending from the post 85 for slidably supporting the other side of the frame.

4. In a hoisting and tilting device, the combination of a body structure, a laterally movable tilting frame adapted to rest flat 90 upon the structure and to receive an object to be tilted, lifting means on one side of the structure connected to the adjacent side of the tilting frame, and lowering means on the structure connected with the hoisting means 95 and said side of the frame to be operated upon the release of the hoisting means and including a device for moving the other side of the frame away from the vertical path of movement of said adjacent side.

5. In a hoisting and tilting device, the combination of a body structure equipped with a post, hoisting means carried by the post and connected to the top thereof, a tilting frame connected at one side with said 105 hoisting means and adapted to engage the structure at its opposite side, a yoke slidable on the post and having connection with the adjacent side of the frame, an arm on the frame projecting beyond the yoke, and lowering means connected to said arm and to said hoisting means adapted to draw the arm 110 down and swing said opposite end of the frame outwardly from the post when the hoisting means is released.

6. In a hoisting and tilting device, the combination of a body structure including spaced apart transverse tracks and uprights at one end of the tracks, a vehicle receiving frame normally resting across the tracks and 120 having rollers on the side remote from the posts adapted to bear on the tracks, and a combined hoisting and lowering mechanism mounted on said posts and having connection with the adjacent side of the tilting 125 frame for forcing said side up and down and tilting the same in the desired angle.

7. In a hoisting and tilting device, the combination of a body structure, a vehicle receiving frame normally resting flat upon 130

the structure, hoisting means mounted on the structure and connected to the side of the frame, and lowering means on the structure connected to the same side of the frame and to the hoisting means and including a spring element for tensioning the frame during its movements.

8. In a hoisting and tilting device, the combination of a body structure, a tilting frame adapted to lie flat upon the structure, hoisting means on the structure connected to one side of the frame for elevating the same, a lever connected at one end to the frame and extending at its lower end from the frame beyond the connection between the frame and the hoisting means, and lowering means connected to said other end of the lever for drawing the adjacent side of the frame down and moving the other side of the frame away from the vertical plane of movement of said adjacent side of the frame.

9. In a hoisting and tilting device, the combination of a body structure, a vehicle receiving frame arranged to lie flat upon the structure for receiving a vehicle, a combined hoisting and lowering mechanism on the structure connected to one side of said frame for raising and lowering the same, and a resilient connection in said hoisting and lowering mechanism for yieldingly holding the frame from advance tilting movement.

10. In a hoisting and tilting device, the combination of a body structure, a vehicle tilting frame arranged on the structure to lie flat to receive a vehicle, a hoisting mechanism on the structure connected to one side of the frame, a lowering mechanism on the

structure connected to the frame, and a resilient connection between the frame and said lowering mechanism.

11. In a hoisting and tilting device, the combination of a body structure, a tilting frame arranged to lie flat upon the structure to receive a vehicle, a hoisting means at each end of the structure connected to the adjacent side and end of the frame, a tensioning device connected to said sides and ends of the frame, and a single operating element connected to said hoisting means and tension device for alternately actuating the same to simultaneously raise and lower the opposite ends of the frame.

12. In a hoisting and tilting device, the combination of a pair of transverse rails, posts rising from the inner ends of the rails, a tilting frame arranged to lie flat across the rails to receive a vehicle thereon, hoisting cables trained over the upper ends of the posts and connected at one end to the adjacent side of said frame, slideable means connecting the said side of the frame to said posts, spring actuated arms pivoted upon said side of the frame and projecting inwardly beyond the posts, tension cables connected to the outer ends of said arms, and a single operating shaft having said hoisting and tension cables wound opposite thereon for raising said side of the frame and for throwing the other side of the frame outwardly over said rails from the posts upon the lowering of the frame.

JOHN H. BURR.
